UNITED STATES PATENT OFFICE

HAROLD G. RICE, OF CHICAGO, ILLINOIS, ASSIGNOR TO INDESTRO MFG. CO., OF CHICAGO, ILLINOIS, A CORPORATION OF ILLINOIS

BOTTLE CAPPER

Application filed March 1, 1930. Serial No. 432,337.

My invention relates to bottle cappers, and has to do particularly with devices which are especially adapted to affix on a bottle a closure of the well-known "crown" type.

An object of my invention is to provide a device which is quickly and easily adjustable for operating upon bottles of various heights.

A further object of my invention is to provide such a device which may be constructed of a relatively small number of simple parts so as to be inexpensive to fabricate and at the same time efficient in operation and rugged.

Various other objects and advantages of the construction will be readily apparent to those skilled in the art from the disclosure herein given.

Referring now to the drawings forming part of this specification and illustrating a preferred embodiment of my invention:

Fig. 1 is a side elevational view of a device embodying my invention, the dotted lines showing the device in capping position;

Fig. 2 is a fragmentary rear elevation of the same;

Fig. 3 is a top plan view of the same;

Fig. 4 is a fragmentary side elevational view on an enlarged scale and showing dotted certain parts in positions assumed by them in the adjustment of the device for bottles of different heights;

Fig. 5 is a sectional view taken on the line 5-5 of Figure 4;

Fig. 6 is a sectional view taken on the line 6-6 of Figure 4, and

Fig. 7 is a bottom plan view of the base of the device.

The illustrated device comprises a base member 10, preferably of sheet metal and stiffened as by corrugations 11, to the upper surface of which may be secured a resilient mat 12 of rubber or the like, for cushioning a bottle which is placed upon the base to be capped. The mat may have an integral boss 13 extending through an aperture in the base 10 for retaining the mat in place. Mounted on the base is a standard 15 which is preferably T-shaped in cross section and may, if desired, be formed of a single member. However, I find it convenient to make the

standard of a pair of angle members 16 and 16', these members being secured together as by means of rivets 17 or the like. The rear flanges 16^a of the angle members 16 and 16' preferably have a depending tongue 18 (Fig. 5) disposed in a slot 19 in the base, while the front flanges 16^b of the angle members are bent forwardly (Fig. 1) to provide a foot 20 secured to the base by means of rivets 21 or the like, a brace bar 22 being provided above the foot 20. Apertures 23 may be provided in the base 10 for screwing the device to a table or bench.

The standard 15 is curved forwardly adjacent the upper portion thereof, as shown in Fig. 1, the front flanges 16^b of the angle members terminating as at 24 below the upper extremities of the angle members. These members project forwardly adjacent their upper extremities and cooperate to form a narrow sleeve 25, this sleeve having outstanding ears 26 secured by means of rivets 27 or the like. The sleeve is perforated with opposite slots 28 which extend vertically through both of the plates 16 and 16', and communicating with these slots there is provided in both the plates a slot 29 extending obliquely downwardly and rearwardly from the slot 28.

A lug 30 is formed on the flanges 16^a of the standard 15 adjacent the upper portion thereof, and to it is pivotally secured, as at 31, a dog 32 (Figs. 2 and 4) comprising a finger piece 33 and a T-shaped latch 34. The purpose of this dog will be explained later.

Pivoted on opposite sides of the upper portion of the standard behind the sleeve 25, as at 37, is a pair of bell crank levers 40. To one arm of each of these levers, which is bifurcated as at 41, is attached a helical tension spring 42. The opposite end of the spring is attached to an aperture 43 adjacent the rear end of a handle 45. This handle comprises a member 46, the forward part of which may be curved, as at 47, so as to seat comfortably in the palm of a person's hand, while the rear portion thereof is formed in a U-shape so as to embrace a member 48 normally forming an extension of the member 46. These two members are permanently secured together by

means of a rivet 49 or the like, and a bolt and nut 50 also secures them when the device is set up for operation. It will be understood that the bolt and nut 50 are removed and the handle folded around the pivot 49 when it is desired to pack the device for shipment, in order to economize on space.

The member 48 of the handle is preferably formed of a plurality of similar bars disposed adjacent each other as at 52, where they are embraced by the member 46 and diverging from each other, as at 53, so that the rear portions 54 (Fig. 5) thereof are in spaced parallel relation. The members 54 are secured by means of rivets 56 or the like to the bell crank levers 40. Extending rearwardly from each of the members 54 is an arcuate lug 58.

Slidable within the sleeve 25 is a reciprocable capping member 60. This capping member may be formed of a pair of similar bars riveted together, as at 61 and 62, and carries adjacent its lower extremity a capping head 63 of well-known construction, the bars extending through the upper wall of the head 63 and being flanged over therein. A plurality of notches 65 are formed in the rear of the bars and it will be noted that the lower faces 66 of these notches are substantially horizontal while the upper faces 67 thereof slope upwardly and outwardly. A pin, rivet or the like 70, connecting the bars 54 of the handle 45, is normally seated within one of the notches 65, so as to pivot the handle 45.

The operation of the device will be apparent from what has gone before. When the device is arranged as shown in Figures 1 and 4 in full lines, a bottle is placed upon the base 10 in substantially the center thereof, and a cap disposed over the opening of the bottle. The operator, grasping the free end 47 of the handle 45, depresses it against the resilient resistance of the springs 42, thus moving the capping member 60 downwardly, as shown dotted in Fig. 1, the pin 70 riding in the vertical slot 28. The capping head 63 engages the cap and secures it upon the bottle. The operator needs thereupon only to release the handle 45 and the springs 42 will promptly move it and the capping member 60 back to the position shown in full lines.

During the first portion of the capping movement of the handle the latter pivots about the point 56, rotating the bell crank slightly counter-clockwise, as shown in Figs. 1 and 4; the bell crank remains practically stationary as the handle approaches horizontal position and shortly thereafter the bell crank begins to rotate in clockwise direction, as the handle moves downwardly. As the handle approaches the dotted position (Fig. 1), the movement thereof is almost entirely about the pivot 37, and hence the capping member is at this point moving downward very slowly in proportion to the angular velocity of the handle. It will thus be seen

that, when the handle is given a motion of uniform speed, the capping member attains a negative acceleration. This is important in that, although a sharp quick movement may be imparted to the handle, the capping member will nevertheless be applied to the bottle with a slow but firm motion, thus avoiding any danger of breaking the bottle.

When it is desired to vary the adjustment of the capping member 60 for a bottle of a different height, the operator merely moves the dog 32 from the position shown in full lines in Figure 4 to the dotted position. Then, depressing the handle 45, the arcuate lugs 58 will become hooked behind the forks 80 of the T-shaped latch member 34, as shown in dotted lines in Figure 4. It will be seen that further downward force applied to the end of the handle 45 results in a slight rearward translatory movement of the handle, 85 the arcuate members 58 sliding along the bifurcations 34. Thus, the pin 70 is moved out of the particular slot 65 of the capping member 60 in which it was disposed and is moved rearwardly and downwardly into the oblique slot 29. Hence, the capping bar 60 is free to slide up and down within the sleeve 25 and the operator may then move it to the desired height. Upon then removing the downward pressure against the handle 45, the springs 42 will immediately restore the device to operative condition, the pin 70 being moved back into engagement with one of the slots 65 of the bar 60.

It will thus be seen that my device is made 100 in an extremely small number of simple parts, and since they are practically all the result of stamping operations, its fabrication is very inexpensive. At the same time, it is rugged and efficient in operation and may be adjusted in a minimum of time for bottles of various sizes.

Various modifications within the spirit of my invention will suggest themselves to those skilled in the art. Hence, I do not wish to be limited to the particular form disclosed or uses mentioned except as set forth in the appended claims, which are to be interpreted as broadly as is consistent with the state of the art.

I claim as my invention:

1. In a device of the class described, a standard, a capping member carried by said standard so as to be vertically reciprocable, and a pivoted handle for actuating said capping member, the pivot of said handle being floatingly carried by and translatable with respect to said standard so that said handle may be brought into and out of operative relation to said capping member, and means resiliently urging said handle into engagement with said capping member and toward an elevated position.

2. In a device of the class described, a standard, a capping member slidably carried

thereby, means for actuating said capping member, means connecting said actuating member to said standard on a translatable pivot whereby said actuating member may be capable of translation into and out of operative relationship with respect to said capping member so as to permit variation of the effective length thereof, and means resiliently urging said actuating member into engagement with said capping member.

3. In a device of the class described, a standard, a capping member having rigidly secured thereto a rack bar slidably carried by said standard, and means floatingly pivoted to said standard and to said bar for reciprocating the latter, said means being laterally shiftable to permit adjustment of said bar so as to vary the effective length thereof.

4. In a device of the class described, a standard, a capping member slidably carried thereby, means for actuating said capping member, means including a link pivotally connecting said actuating member to said standard whereby said actuating member may be capable of translation into and out of operative relation with respect to said capping member, pivotal means for operatively connecting said actuating means to said capping member, said last-named pivotal means being readily engageable and disengageable at a plurality of points on said capping member, and means resiliently urging said actuating means into engagement with said capping member.

5. In a device of the class described, a standard, a capping member including a rack bar slidably carried by said standard, a link pivoted to said standard, an operating lever pivoted to said link and engageable with said bar at a plurality of points on the latter, and resilient means for retaining said lever in operative engagement with said capping member.

6. In a device of the class described, a standard, a capping member slidably carried by said standard, a link pivoted to said standard, an operating lever pivoted to said link and engageable with said capping member at a plurality of points on the latter, and resilient means urging said capping member toward elevated position and said lever into engagement with said capping member.

7. In a device of the class described, a standard, a capping member comprising a bar slidably carried by said standard, means for actuating said capping member and engageable with said bar at a plurality of points thereon, movable means connecting said actuating means to said standard, whereby said actuating means may be moved into and out of cooperative relationship with said bar, so that the latter may be adjusted to vary the effective length of said capping member, and means connected to said movable means and to said actuating means resiliently urging

said actuating means into cooperative engagement with said bar and the latter upwardly.

8. In a device of the class described, a standard, a capping member carried by said standard so as to be vertically reciprocable, pivoted means for actuating said capping member, the pivot of said last-named means being translatable with respect to said standard so that said actuating means may be brought into and out of operative relationship to said capping member, and means carried by said standard and movable into engagement with said actuating member for cooperating therewith to effect translation thereof out of engagement with said capping member upon the application of a downward force to the operating end of said actuating member.

9. In a device of the class described, a standard, a capping member slidably carried by said standard, means pivoted to said standard and to said capping means for reciprocating the latter, and means carried by said standard and movable into engagement with said actuating member for cooperating therewith to effect translation thereof out of engagement with said capping member upon the application of a downward force to the operating end of said actuating member.

10. In a device of the class described, a standard, a capping member slidably carried thereby, means pivotally carried by said standard for actuating said capping member, means whereby said last-named means may co-act with said capping member at a plurality of points so as to vary the effective length of said member, and means carried by said standard and movable into engagement with said actuating member for co-operating therewith to effect translation thereof out of engagement with said capping member upon the application of a downward force to the operating end of said actuating member.

11. In a device of the class described, a standard, a capping member carried by said standard so as to be vertically reciprocable, pivoted means for actuating said capping member, the pivot of said last-named means being translatable with respect to said standard so that said actuating means may be brought into and out of operative relationship to said capping member, and means carried by said standard and movable into engagement with said actuating member for cooperating therewith to effect translation thereof out of engagement with said capping member upon the application of a force to the operating end of said actuating member, the latter fulcruming against said last-mentioned means, so that the effective length of said capping member may be adjusted.

12. In a device of the class described, a standard, a capping member carried by said standard so as to be vertically reciprocable, a handle for actuating said capping member, means secured to said standard and pivotally

- mounting said handle whereby said handle may be moved into and out of engagement with said capping member in order that the effective length of the latter may be varied, 5 said last-mentioned means also functioning to convert a motion of constant speed applied to said handle into a motion of decreasing speed on the part of said capping member when the handle is moved downwardly, and 10 resilient means connected to said handle and to said handle mounting means for urging said handle into cooperative engagement with said capping member and the latter upwardly. 15 13. In a device of the class described, a standard, a capping member carried by said standard so as to be vertically reciprocable, a handle for actuating said capping member, said handle being mounted for rotary and 20 also for transverse motion relative to said capping member, a bell crank lever pivoted to said frame, said handle being pivoted to one arm of said bell crank lever, means carried by said handle and engageable with said capping member for reciprocating the latter, and a resilient member connected to said handle and to the other arm of said bell crank lever for urging said handle into engagement with said capping member and the 25 latter upwardly. 30 14. In a device of the class described, a standard, a capping member carried by said standard so as to be vertically reciprocable, a handle for actuating said capping member, 35 said handle being mounted for rotary and also for transverse motion relative to said capping member, a bell crank lever pivoted to said frame, said handle being pivoted to one arm of said bell crank lever, means carried by said handle and engageable with said capping member for reciprocating the latter, a resilient member connected to said handle and to the other arm of said bell crank lever for urging said handle into said capping member upon the application of a force to the operating end of said actuating member, and a pintle carried by said actuating member and engageable with said notches.

16. In a device of the class described, a standard, a capping member carried by said standard so as to be vertically reciprocable, a handle for actuating said capping member, a bell crank pivoted to said standard and having one arm thereof pivoted to said handle, whereby the latter is translatable with respect to said standard and may be brought into and out of operative relation with said capping member, pivotal means for operatively connecting said handle to said capping member, said last-named pivotal means being readily engageable and disengageable at a plurality of points on said capping member, and a resilient member connected to the other arm of said bell crank and to said handle for urging the latter into operative engagement with said capping member.

CERTIFICATE OF CORRECTION.

Patent No. 1,904,328.

April 18, 1933.

HAROLD G. RICE.

It is hereby certified that the above numbered patent was erroneously issued to "Indestro Mfg. Co., of Chicago, Illinois, a corporation of Illinois," whereas said patent should have been issued to "Indestro Manufacturing Corp., a corporation of Illinois," as assignee by mesne assignments of the entire interest in said invention, as shown by the records of assignments in this office; and that the said Letters Patent should be read with this correction therein that the same may conform to the record of the case in the Patent Office.

Signed and sealed this 29th day of August, A. D. 1933.

M. J. Moore.

(Seal)

Acting Commissioner of Patents.
